DISPENSER

Joseph P. Kuertz, Cincinnati, Ohio

Application February 27, 1935, Serial No. 8,454

1. Claim. (Cl. 312—114)

This invention relates to a display dispensing container or case of a type primarily for disposition upon a sales counter of a retail store for holding and displaying a staple commodity in bulk quantity for retail dispensation thereof.

The container or case is particularly adapted for holding a prepared food product as potato chips, which are adversely affected upon exposure to atmosphere, necessitating it to be kept in a closed vessel for maintaining its quality and crispness. It has been experienced that the retail sales of such commodity are materially increased when displayed in bulk quantities.

An object of the invention is to provide a display dispensing container or case, primarily for holding a commodity in bulk quantity, from which dispensation is made in retail quantities, with a transparent shell mounted within a pedestal, of a structure admitting display of the entire contents of the case and from which the contents can be scooped or taken out through a side door opening at the bottom of the case.

Various other features and advantages are more fully set forth in the description of the accompanying drawings, in which:

Figure 1 is a front elevation of the improved display, dispensing container.

Figure 2 is a side elevation thereof.

Figure 3 is a perspective view of the pedestal as a support and bottom of the container with a door mounted thereon in open position.

Figure 4 is an enlarged section on line 4—4.

Figure 1.

Figure 5 is an enlarged top plan view of the pedestal.

Referring to the drawings, 1 indicates a pedestal, preferably of circular form, providing a support for the container, and a bottom or base 2 for a cylindrical shell 3, preferably of glass, for full vision of the entire contents of the container. The pedestal has an outwardly and downwardly curved rim 4 as a marginal rest for the base or bottom 2 to sustain the same in a slightly elevated plane, and with an upstanding flange 5, and internally forming a rabbet 6 for recessing and securing the lower end of the cylindrical shell 3 within the pedestal. The base of the rabbet 6 is slightly offset from the top surface or plane of the base to provide a curved curb for the base, thereby avoiding any sharp corners or crevices which would collect sediment that may be deleterious to the product stored within the container.

The container primarily is intended for displaying and dispensing a food product such as

potato chips, which carry grease that, unless extreme precaution is taken, readily becomes rancid. Any accumulation of such matter that is allowed to collect and remain within corners or crevices of the container for any period of time becomes rancid, readily spoiling or contaminating a replenishing fresh supply of potato chips stored within the container, rendering it unfit for sale.

The interior of the glass shell terminates flush with the top of the curb, the lower end of the shell being recessed within the pedestal and telescoped with a flange and secured to the flange preferably by a plastic packing inserted between the periphery of the shell and flange, providing a hermetically sealed joint.

The pedestal has a door frame or snout 7 integral therewith and extending vertically above the normal elevation of the pedestal with the bottom of the frame continuous with or constituting an extension of the base 2. A door 8 is pivoted to the front end of the bottom of the frame to swing upwardly to close the opening, and is marginally flanged to overlap the front margins of the frame. The front edges of opposite side walls 9—9 of the door frame are inclined to allow the door to swing inward of a dead central vertical line, so that the door will remain closed under gravity. The lower edge of the door at its exterior side is provided with a beading 14 integral therewith for engaging with the front edge of the base of the frame or extension of the platform, limiting the opening swing of the door and holding the same forthward, as a shelf, in plane with the platform, of advantage in scooping the contents from the case.

The exterior sides of the walls of the frame and crown or top thereof are provided with a pair of spaced flanges 10—11, forming a channel for the reception of the portion of the shell 3 extending thereabout, and adapting the same to be sealed therein by a plastic packing filled into the channel at the opposite sides of the shell for forming a sealed joint.

The outer flange 10 is continuous with the upturned flange 5 of the pedestal and the glass shell or cylinder 3 is cut out to fit over the door frame.

A deflector or shield is fixed to the crown of the door frame and extends laterally inwardly into the interior of the shell and follows the contour of the crown of the door frame to bridge the door opening. The shield serves to sustain the contents of the shell thereabove and deflects or sheds the same inward in its descent, avoiding that portion of the contents below the shield from being

spread into the door opening and against the door, and spill upon opening the door.

A removable cover 13 is disposed upon the open top of the shell, adapting the same to be uncovered for filling and also for convenient access into the shell to cleanse the same.

The case or container is primarily contemplated for displaying a prepared food commodity as potato chips in bulk quantity and for dispensation therefrom in retail quantities. It is preferable to have the case disposed upon a sales counter in a retail store to influence sales, but without assuming too great a space area, and for convenience it is desirable to have the door opening 10 at one side toward the bottom of the case to allow the contents to be scooped out from the rear side 15 of the counter upon which the case is disposed.

It heretofore has been customary to construct a display case with a pedestal of a height in proportion to the height of the door opening, which is objectionable as a large amount of the contents of the case is contained within the pedestal out of display vision, materially affecting sales when the supply is reduced within the holding capacity of the pedestal. The customers, under such circumstances, cannot readily observe the condition of the product and this enables unscrupulous dealers sometimes, due to lag in sales, to dispose of a stale product, in injury to the market of a distributor or manufacturer who advocates discarding any unstaple portion or after it has reached a prescribed age when it has lost its crispness and fresh flavor.

The improved case provides for visibility of its entire contents, and a customer can readily observe whether it is of the same quality throughout. The low form of pedestal with the door frame rising thereabove, while necessitating cutting out 5 the glass shell to engage it about the door frame for providing a side opening, allows the lower edge of the shell to substantially rest upon the platform of the pedestal forming the bottom closure for the shell, thereby exposing only a 10 minimum metal surface of the pedestal to the interior of the case which is either enamel surface finished or covered with a renewable lining.

Having described my invention, I claim:

In a display dispensing case, a pedestal providing a platform, a rim about the platform for sustaining the same, an upturned peripheral flange for the upper side of the platform for telescopically receiving the open end of a cylindrical shell for mounting the shell upon the pedestal, 20 a door frame integral with the pedestal and upstanding therefrom, the outer side of the walls of the door frame having spaced flanges projecting therefrom to form a groove for the reception of the portion of the shell thereabout with the outer 25 flange continuous with said peripheral flange, a door hingedly secured to the pedestal at the bottom of the door frame for extending in a plane with the platform when the door is open, and a shield fixed to the inner upper end of the door 30 frame for providing a hood within the shell over the frame door opening.

JOSEPH P. KUERTZ.
